DESIGN FOR A PROJECTOR

Otto E. Trautmann, Irondequoit, N. Y., assignor
to Bausch & Lomb Optical Company, Rochester,
N. Y., a corporation of New York

Application March 17, 1937, Serial No. 68,239

Term of patent 14 years

To all whom it may concern:

Be it known that I, Otto E. Trautmann, a citizen of the United States and a resident of the town of Irondequoit, county of Monroe, and State of New York, have invented a new, original, and ornamental Design for a Projector, of which the following is a specification, reference being had to the accompanying drawing, forming a part thereof.

The figure is a perspective view of a projector embodying my new design, the essential features of the design being shown in full lines.

I claim:

The ornamental design for a projector substantially as shown and described.

OTTO E. TRAUTMANN.
